UNITED STATES PATENT OFFICE.

HERMAN C. PRIEBE, OF CHICAGO, ILLINOIS.

TANK-CAR UNDERFRAME.

1,111,492.

Specification of Letters Patent. Patented Sept. 22, 1914.

Application filed January 14, 1910. Serial No. 537,982.

To all whom it may concern:

Be it known that I, HERMAN C. PRIEBE, a citizen of the United States, residing in Chicago, in the county of Cook and State 5 of Illinois, have invented a new and useful Improvement in Tank-Car Underframes, of which the following is a specification.

My invention has for an object the providing of a tank-car with an underframe 10 construction wherein the center-sills directly and securely support the tank and directly sustain, but yieldingly cushion, the end-thrust of said tank; and my invention has for further objects such other improvements 15 in structure or function as may be found to obtain in the devices hereinafter described or claimed.

In the accompanying drawings, forming a part of this specification, and in which 20 like reference numerals indicate like parts in all the figures, Figure 1 is a longitudinal sectional view showing the middle portion and one of the duplicate ends of a tank-car underframe embodying my invention; Fig. 2 is a section on the line 2—2 of Fig. 1; Fig. 3 is a section on the line 3—3 of Fig. 1; Fig. 4 is a section on the line 4—4 of Fig. 1.

10—10 are the channel iron center-sills 20 of the underframe, and 11 is the tank. 12—12 are saddle castings rigidly secured to the bottom of the tank, the elongated top member 13 of these said castings being shaped to conform with the curvature of 35 the tank-bottom that it cradles and is riveted to. The longitudinal shoulders 14 of said castings rest on and bear down upon the top face of the upper flanges of the sills, while the downwardly projecting 40 lower members 15 of said castings are fitted within and between the opposed inner faces of the vertical webs of the said sills, the said cradle-castings being thus supported upon and socketed to the sills and adapted 45 to have a sliding movement longitudinally upon the top flanges of the sills, such sliding movement being resisted by the considerable friction between said sill-flanges and the aforesaid cradle-casting shoulders that 50 rest upon said flanges. The downwardly projecting members 15 of each cradle-casting are provided with transverse longitudinally elongated keyways 16, at the respectively opposite ends of said members and 55 respectively registering with corresponding and equal longitudinally elongated keyways

in the opposed vertical webs of the center-sills. A horizontal flattened key 17, of a width substantially less than the length of the aforesaid keyways, is passed transversely through each mutually registering series of keyways in the sills and cradle-casting, thus securing the cradle-casting to the sills and at the same time permitting it a limited longitudinal sliding movement 60 with respect to the sills, the extent of such movement being limited by the difference between the length of the keyway slots and the width of the keys, the possible movement being obviously just twice this difference. The keys are retained in place laterally by the cotter-pins 18 inserted in their respectively opposite ends. Between the two keys transverse of the respectively opposite ends of each cradle-casting, there are 65 inserted three concentrically compound springs 19, one being positioned between the sills and one on either side of the sills, the opposite ends of the said springs bearing against the respectively opposed vertical edges of the said transverse keys and thus constantly tending to hold said keys spread apart to the farthest limit permitted by the aforesaid elongated keyways in the cradle-casting and sills. Each of said compound springs is retained in place, horizontally, by a retaining tube 20 whose ends are in slotted engagement with the respectively opposed keys, each such retaining tube inclosing the inner and being encircled by the outer of the two coiled springs that together constitute each of the aforesaid concentrically compound springs. It is obvious that any end-thrust of the tank, resulting from a buffing shock or other cause, will be transmitted through the cradle-castings and keys and be directly sustained by the sills, but will be yieldingly cushioned by the compression of the aforesaid springs and will be limited by the possible longitudinal sliding movement of the cradle-castings in respect to the sills. This cushion provides that the tank is relieved of shock or strain to which it would otherwise be subjected by any buffing of the car 80 underframe; and at the same time the tank is supported on and secured to the underframe in a manner that is of extreme simplicity and efficiency. Any tendency of the tank to lateral swaying may be additionally provided against by the saddles 21 mounted 85 on the lateral members of the body bolsters.

22, and shaped to conform with the curvature of the bottom of the tank, such saddles also supporting the longitudinal side-beams 23 that extend from bolster to bolster and 5 additionally support the lower portion of each side of the tank. These saddles and side-beams relieve the cradle-castings and keys from strain that would otherwise be put upon them by any tendency of the tank 10 to lateral swaying.

The cushioning effect of the spring devices co-operates with the friction of the shoulders of the cradle-casting upon the top flanges of the sills, and these two yielding 15 resistances are together capable of overcoming and cushioning a shock greatly in excess of, or even several times, the amount of the load that is so supported on the sills. One of these cradle-castings is positioned 20 near each body bolster, and a third may be positioned at the middle of the tank, thus providing either two or three of them intermediate the body bolsters or in the length of the tank; or only the middle cradle-casting 25 may be retained, to support and cushion the tank at the middle of the car, and then the opposite ends of the tank may be supported in the usual saddles over the bolsters or otherwise.

30 My invention is hereinabove set forth as embodied in one particular form of construction, but I do not limit it thereto or to less than all the possible forms in which the invention as hereinafter claimed may 35 be embodied and distinguished from any prior devices for like purpose.

I claim:—

1. In a tank-car, in combination: a tank; center-sills; a cradle-member rigidly secured to the bottom of the tank and supported upon and socketed to the center-sills, said member bearing down on and being 40 slideable longitudinally of said sills; transverse keys passed through 45 registering key-ways in said center-sills and cradle-members, the key-ways in the said mutually co-operating members being elongated to permit the aforesaid sliding of said member on said sills; and spring-devices 50 adapted to yieldingly cushion said member at either limit of said longitudinal movement: substantially as specified.

2. In a tank-car, in combination: a tank; center-sills; a cradle-member rigidly secured 55 to the bottom of the tank and supported upon and socketed to the center-sills, said member bearing down on and being slideable longitudinally of said sills; a pair of transverse keys passed through key-ways in the 60 opposite ends of the cradle-member and through respectively registering key-ways in said center-sills, the key-ways in the said mutually co-operating members being elongated to permit the aforesaid sliding of said member on said sills; and a spring interposed 65

and retained between said pair of opposed keys, to yieldingly cushion said member at either limit of said longitudinal movement; substantially as specified.

3. In a tank-car, in combination: a tank; center-sills; a cradle-member rigidly secured to the bottom of the tank and supported upon and socketed to the center-sills, said member bearing down on and being slideable longitudinally of said sills; engaging devices adapted to secure together said center-sills and cradle-member and to permit and limit the aforesaid sliding of said member on said sills; and spring-devices 75 adapted to yieldingly cushion said member at either limit of said longitudinal movement; substantially as specified.

4. In a tank-car, in combination: a tank; center-sills, a cradle-member rigidly secured to the bottom of the tank and supported 80 upon and socketed to the center-sills, said member bearing down on and being slideable longitudinally of said sills; a pair of transverse keys passed through key-ways in the opposite ends of the cradle-member and 85 through respectively registering key-ways in said center-sills; the key-ways in the said mutually co-operating members being elongated to permit the aforesaid sliding of said member on said sills; and multiple springs 90 interposed and retained between said pair of opposed keys, to yieldingly cushion said member at either limit of said longitudinal movement; substantially as specified.

5. In a tank-car, in combination: a tank; center-sills; a cradle-member rigidly secured to the bottom of the tank and supported upon and socketed to the center-sills, said member bearing down on and being slideable 100 longitudinally of said sills; a pair of transverse keys passed through key-ways in the opposite ends of the cradle-member and through respectively registering key-ways in 105 said center-sills, the key-ways in the said mutually co-operating members being elongated to permit the aforesaid sliding of said member on said sills; and concentrically 110 compound springs interposed and retained between said pair of opposed keys, to yieldingly cushion said member at either limit of 115 said longitudinal movement; substantially as specified.

6. In a tank-car, in combination: a tank; center-sills; a cradle-member rigidly secured to the bottom of the tank and supported 120 upon and socketed to the center-sills, said member bearing down on and being slideable longitudinally of said sills; a pair of transverse keys passed through key-ways in the opposite ends of the cradle-member and 125 through respectively registering key-ways in said center-sills, the key-ways in the said mutually co-operating members being elongated to permit the aforesaid sliding of said member on said sills; and a spring inter- 130

- posed and retained between said pair of opposed keys, to yieldingly cushion said member at either limit of said longitudinal movement, said spring being held positioned by a retaining tube that is in slotted engagement with said keys; substantially as specified. 5
7. In a tank-car, in combination: a tank; center-sills; a cradle-member rigidly secured to the bottom of the tank and supported upon and socketed to the center-sills, said member bearing down on and being slideable longitudinally of said sills; a pair of transverse keys passed through key-ways in the opposite ends of the cradle-member and through respectively registering key-ways in said center-sill, the key-ways in the said mutually coöoperating members being elongated to permit the aforesaid sliding of said member on said sills; and concentrically compound springs interposed and retained between said pair of opposed keys, to yieldingly cushion said member at either limit of said longitudinal movement, said springs being held positioned by a retaining tube that is in slotted engagement with said keys and that incloses the inner and is encircled by the outer of the mutually concentric springs; substantially as specified. 15
8. In a tank-car, in combination: a tank; center-sills; a cradle-member rigidly secured to the bottom of the tank and supported upon and socketed to the center-sills, said member bearing down on and being slideable longitudinally of said sills; a transverse key passed through mutually registering key-ways in said center-sills and cradle-members, the key-ways in the said mutually coöoperating members being elongated to permit the aforesaid sliding of said member on said sills; and spring-devices adapted to yieldingly cushion said member at either limit of said longitudinal movement; substantially as specified. 30
9. A car structure including a tank; a supporting structure therefor upon which the tank may move longitudinally with respect to the supporting structure; a connection located between the ends of the tank and rigidly secured to the bottom of the tank and moving upon the supporting structure; means for preventing vertical movement between said connection and the tank supporting structure without preventing said longitudinal movement of the tank; and supports for the tank upon each side of said connection, upon which supports the tank may slide. 45
10. A car structure including a tank; a supporting structure therefor upon which the tank may move longitudinally with respect to the supporting structure; a connection located between the ends of the tank and rigidly secured to the bottom of the tank and sliding upon the supporting structure; means for preventing vertical move- 50
- ment between said connection and the tank supporting structure without preventing said longitudinal movement of the tank; and supports for the tank upon each side of said connection, upon which supports the tank may slide. 70
11. A car structure including a tank; a supporting structure therefor upon which the tank may move longitudinally with respect to the supporting structure; a connection taking part in holding the tank down and which is attached to the tank and is moved by the tank upon and longitudinally of the supporting structure; and means for preventing vertical movement between said connection and the tank supporting structure without preventing longitudinal movement of said tank and connection. 75
12. A car structure including a tank; a supporting structure therefor upon which the tank may move longitudinally with respect to the supporting structure; a connection taking part in holding the tank down and which is attached to the tank and caused to slide by the tank upon the supporting structure; and means for preventing vertical movement between said connection and the tank supporting structure without preventing said longitudinal movement of the tank and connection. 80
13. A car structure including a tank; a supporting structure therefor upon which the tank may move longitudinally with respect to the supporting structure; a connection located between the ends of the tank and taking part in holding the tank down and which is attached to the tank and caused to slide by the tank upon the supporting structure; means for preventing vertical movement between said connection and the tank supporting structure without preventing said longitudinal movement of the tank and said connection; and supports for the tank upon each side of said connection, upon which supports the tank may slide. 90
14. A car structure including a tank; a supporting structure therefor upon which the tank may move longitudinally with respect to the supporting structure; a connection taking part in holding the tank down and which is attached to the tank and is caused to slide by the tank upon and longitudinally of the supporting structure; and means for preventing vertical movement between said connection and the tank supporting structure without preventing said longitudinal movement of the tank and connection. 100
15. In a tank car provided with center sills and a removable tank mounted thereon, a cushioned anchoring means for said tank and means extending through said center sills and adapted to limit the longitudinal movement of the tank on said sills. 110

16. In a tank car provided with center sills and a removable tank, means to permit independent movement of the tank with relation to said sills and coöperating means extending through said sills adapted to unite said tank and sills.

In testimony whereof I hereunto set my

hand in the presence of two subscribing witnesses.

HERMAN C. PRIEBE.
